UNITED STATES PATENT OFFICE.

JOHANN GYURIS, OF BUDAPEST, HUNGARY, ASSIGNOR TO HUNGARIAN ELEKTHER-MAX COMPANY LIMITED, OF BUDAPEST, HUNGARY.

PROCESS OF MOUNTING RESISTANCE ELEMENTS OF ELECTRIC HEATERS.

No Drawing.

Application filed April 7, 1921. Serial No. 459,346.

To all whom it may concern:

Be it known that I, JOHANN GYURIS, citizen of the Kingdom of Hungary, residing at Budapest, Kingdom of Hungary, have invented certain new and useful Improvements in Processes of Mounting Resistance Elements of Electric Heaters, of which the following is a specification.

My invention relates to electric heaters, such as are used in connection with certain domestic appliances, for example, flat-irons, toasters and cookers, heaters or radiators, etc., and consists in a method of so mounting the resistance elements of such devices that they will be more efficient and durable than heretofore.

For the efficiency and durability of electric heaters, it is of special importance that the heat in passing from the heater to the surface to be heated, encounters the least possible resistance. The consequence of a high resistance, for instance of the interposition of an insulating layer of a considerable thickness, is that the heater has to be heated to a point above the working temperature required and is accordingly exposed to a great heat which results in the premature burning out of the thin wire resistance elements of the heater. Another advantage of facilitating the passage of heat between the heater and the surface to be heated, consists in the heat being rapidly carried away from the resistance element through which the current is passing, whereby it is less exposed to the danger of burning out.

Bearing in mind the above considerations, it has been repeatedly attempted to replace the generally used heaters, in which the thin metal wire is wound on solid refractory materials or embedded in such materials, the transmission of heat by which is very bad, by other heaters in which the metal wire is in direct contact with the surface to be heated. It has been for instance attempted to put the metal resistance mixed with glass or enamel material, on the insulator, and in some cases on the surface to be heated itself, and to burn it in. Further, a process has been proposed in which the surface to be heated is spread over with easily melting precious metals in varnish-like solution, the metal separating from the solution only during the burning. The essential disadvantage of this process is that it can be used only with precious metals,

but not with the cheaper ordinary resistance metals such as nickel and nickel alloys, owing to which the process is very expensive. Moreover, the process can be used only when the surface to be heated is made of a non-conducting material, owing to which however the transmission of heat again becomes incomplete. Finally, between the heat expansion coefficient of the resistance metal and that of its supporting surface, there are considerable differences which result in the resistance element becoming detached on being heated.

Another method of mounting the resistance element consists in embedding it in a plastic and subsequently setting material, such as clay or shellac, etc. This process also fails to give the result desired, as the material in which the resistance is embedded, always has a heat-insulating effect and thus interferes with the transmission of heat. Moreover, in this case also the difference in the heat expansion coefficients becomes noticeable. Attempts to select a material for embedding the resistance, the heat expansion coefficient of which is close to that of the resistance, failed to give a satisfactory result, as it is difficult to find a material of such composition, and also because even when the heat expansion coefficient of the material agrees more or less with that of the heating resistance, this agreement never exists simultaneously also in respect of the metal of the surface to be heated. To this must also be added the difficulty that the material, more particularly when interchangeable heating insertions are used, never fits the surface to be heated accurately, so that the distance between the points at which heat is generated, and the points where it is transmitted, is never the same throughout, and single points of the heating resistance are overheated and burnt out after a short time.

All these disadvantages are eliminated by the present invention, which is based on the discovery that the surface to be heated can be utilized directly as a support for the heating resistance, and that the differences between the various heat expansion coefficients are equalized by embedding the heating resistance in a thin yielding layer and securing it to the surface to be heated by means of a film-like layer of adhesive. The distance between the points where the heat is

generated, and those where it is transmitted, is thereby rendered so small that the heat passes practically unimpeded from the heating resistance to the material to be heated, 5 and the apparatus built according to the invention shows a particularly high degree of efficiency and a durability by far exceeding that of known apparatus. Owing to the selection of the yielding, preferably felt-like 10 material for embedding, the material can follow all the movements caused by the heating, both of the heating resistance and of the supporting surface, and the layer of adhesive used for securing the material can be 15 so thin that the effect of the differences in the heat expansion coefficients is imperceptible in it.

Exhaustive experiments and measurements have shown that an insulating layer of adhesive of the thickness of 0.03 to 0.05 mm., 20 together with a layer of an embedding material which is 0.1 to 0.5 mm. thick and also insulating, is sufficient for ensuring a complete insulation for instance at 110 volts 25 and at a temperature of 600° C., whilst hitherto for the same purpose insulating bodies at least 1 to 8 mm. thick had to be used. Owing to the metal wire, constituting the heating resistance element, being heated 30 only to a few degrees above the desired working temperature, the transmission of heat taking place quite directly, the strain on the metal wire at the same working temperature is considerably less, and its durability exceeds that of the old heaters considerably.

For securing the embedding material, any insulating adhesive that adheres well both to the surface to be heated and to the embedding material, can be used. A very dilute solution of equal parts of water and water glass, containing in suspension finely ground clay, kaolin, asbestos powder, etc., 40 has proved particularly suitable. A film-like layer of such a glue has the property of adhering fast and of following any expansions and warping of the supporting surface, without becoming detached or cracked.

The expanding, preferably felt-like embedding material must be electrically insulating and fireproof. These conditions are best fulfilled by asbestos paper of a thickness of 0.1 to 0.5 mm. Asbestos paper has further the advantage that it can be 50 made of absolutely uniform thickness, so that the heating resistance is at every point at the same distance from the surface to be heated. The resistance wire is for instance secured to a layer of asbestos paper by 55 using templates and then covered with a similar second layer of asbestos paper. The two layers of asbestos paper might be stuck together and preferably by means of the above mentioned adhesive consisting of 60 water, water glass and clay, etc. The em-

bedding material is then secured by means of a thin layer of adhesive to the surface to be heated. The securing is preferably effected under pressure and with heating, owing to which the excess of adhesive is expressed or evaporated. One layer of the yielding embedding material might also be replaced by a layer of adhesive placed directly on the surface to be heated, in which case this layer of adhesive must be somewhat 75 thicker.

The use of pressure when securing the embedding material to the surface to be heated, is advantageous, because the resistance body is then firmly pressed into the embedding 80 material. In this case the sticking together of the two layers of the embedding material is not required, but nevertheless when using asbestos paper, it is advisable to moisten it.

The embedding material insulates the coils 85 of the heating resistance from each other and from the surface to be heated, and prevents oxidation of the resistance.

Before putting on the adhesive, it is advisable to clean the surface to be heated from 90 any impurities, more particularly from grease, in order to ensure good adhesion.

The construction of the heater according to this invention may be for instance, carried out in the following manner.

The surface to be heated is cleaned and coated with a layer of adhesive. This layer, while still moist, is covered with a piece of thin (0.1 to 0.5 mm. thick) asbestos paper which is preferably moistened or coated with the adhesive and must cover those places where the metal wire forming the resistance is to be placed. The metal wire put in place is covered with another layer of asbestos paper, and the two layers of asbestos paper are carefully smoothed out in order to remove any air. The ends of the metal wire, which were already provided with thicker contact parts which are good conductors of current, are secured, with the use of thicker asbestos paper and of the same adhesive, to the surface to be heated. After the metal wire has been secured, the whole surface to be heated, or the whole apparatus, is surrounded, before the adhesive and the layers of asbestos papers become dry, from the outside with a thicker (about 5-30 mm. thick) layer of asbestos powder or sand, placed in suitable moulds into a press under pressure slowly allowed to dry and finally heated to 150-1000°. After the burning, it is preferable to pass the current through the metal wire for a certain length of time. The layer of asbestos powder or sand assists 110 quick absorption of the moisture, and uniform transmission of the pressure.

When making flat heaters, such as flat irons, level radiator surfaces, cooking range plates, etc., the metal wire to which has been 115 gives the proper shape, may also be secured

to asbestos paper, either by sticking, for instance with the above mentioned suspension of clay, etc., in a mixture of water and water glass, or by threading through, or by 5 sewing on with threads which are destroyed during the heating, etc. The metal wire is then covered with a second layer of asbestos paper. The surface to be heated is coated in the manner described with a layer of adhesive, whereupon the layers of asbestos paper supporting the metal wire are put in place, and finally the process is continued in the manner already described.

10 Heating resistances made in the manner described, may also be made and put on the market as independent products. To that end, the heating resistance is mounted in the manner indicated in a thin, flexible or yielding and plastic insulating material, or into a 15 plastic insulating and binding material arranged between two non-plastic, but flexible, insulating surfaces, so that the heating resistance generally constituted by thin metal wire, is held fast in its position, and its coils 20 are insulated from each other as well as from the surface to be heated. This gives a membrane-like heating body, the thickness of which scarcely exceeds that of the thin (about 0.2 mm. thick) metal wire constituting 25 the heating resistance. The insulating layer of this heater is therefore extraordinarily thin, owing to which the transmission of heat is almost as perfect as if the heating resistance were secured direct to the 30 surface to be heated, while owing to the good transmission of heat, any overheating and burning out of the heater do not take place even when the heater apparatus into which the heating body is built, is standing 35 for a long time under current. The heating body is perfectly soft, flexible and elastic, so that it fits completely any bends, uneven 40 portions of the surface to be heated, which is of paramount importance as regards the 45 transmission of heat. The heating resistance is completely embedded in the insulating material, owing to which the heating resistance is firmly held in its position by the insulating material itself, and the insulating 50 material encloses the heating resistance in a perfectly air-tight manner, so that no oxidation of the heating resistance can take place. The air-tight arrangement does not in any 55 way affect the flexibility of the heater.

60 In manufacturing the heater, the proceeding may be such that the metal wire constituting the heating resistance, is wound on one of the insulating plates in the form of flat windings, the resistance is then covered with the second insulating plate and the whole pressed together, so as to produce a heater which is very thin and flexible.

65 The insulating plates may be made of any thin flexible or yielding insulating material. It has been found particularly advantageous

however to use asbestos paper in which the windings of the metal wire are embedded during the pressing. Other insulating substances may however also be used, but if complete connection of the insulating plates 70 and the heating resistance cannot be obtained by compression, the heating resistance must be held fast between the insulating plates by a binding means. As already stated, this binding means may be the above 75 mentioned adhesive. The use of such a binding means is moreover advantageous even when the heating resistance is placed between two insulating plates such as asbestos paper, as it improves the strength of 80 the connection and ensures better insulation. When a binding means is used, the heater is dried before or after pressing.

When using suitable insulating materials, the heating resistance may be placed in 85 them during the manufacture of the insulating materials.

The winding of the metal wire, the drying and the pressing may be effected in any 90 desired manner. Between the insulating layers may also be placed several heating resistance which may then be connected in series or in parallel. During the winding, care must be taken to leave free the two ends of the metal wire. These two ends of the wire may be if necessary soldered to contact 95 plates, corresponding recesses being formed in the heating apparatus, so that the said heater is at once ready after the contacts are 100 inserted.

The thickness of the heating bodies connected in the above manner to the surface to be heated, is very small (0.4-0.5 mm.) so that the best possible transmission of heat is obtained. The heating bodies are not sensitive to variations of the outside temperature, they are extraordinarily fireproof and retain 105 their insulating capacity without change even at high temperatures.

According to this invention, existing apparatus, for instance ordinary cooking vessels, pots (enamelled or otherwise), gas and coal flat irons, etc., may be adapted in a simple manner for electric heating.

What I claim is:

1. The method of mounting the resistance elements of electric heaters, which consists in embedding the same in a yielding insulating fireproof material, and securing the latter to the surface to be heated by a thin 120 layer of insulating adhesive substance.

2. The method of mounting the resistance elements of electric heaters, which consists in securing them between two layers of asbestos paper by means of an insulating adhesive.

3. The method of mounting the resistance elements of electric heaters, which consists in attaching them, by means of an insulating adhesive substance, to a yielding sheet of in-

4
sulating material, and securing the latter to the surface to be heated by means of said adhesive substance.

4. The method of mounting the resistance element of an electric heater, which consists in securing it on a sheet of asbestos paper by means of an insulating adhesive, and securing said sheet to the surface to be heated by means of said adhesive.

5. The method of mounting the resistance element of an electric heater, which consists in securing it to a sheet of flexible insulating fireproof material by means of an adhesive

of water, water glass and a refractory powder, and securing said sheet to the surface to be heated by means of the same adhesive substance.

6. The method of constructing a resistance element, which consists in securing it to asbestos paper by means of an insulating adhesive substance, whereby said element can be applied to any desired surface to be heated.

In testimony whereof I affix my signature.

JOHANN GYURIS.
